ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

CENTER SELVAGE MOTION

Application filed November 12, 1928. Serial No. 318,916.

This invention relates to improvements in center selvage motions for looms and it is the general object of the invention to provide such a motion which will operate with sets of needles moving in opposite directions and reciprocated vertically and displaced laterally by a single driving unit.

When weaving a comparatively narrow fabric on a relatively wide loom it is customary to weave two fabrics side by side from the same warp and filling but separate the same by a selvage motion so that when cut apart each fabric will have a selvage on both edges. In my prior Patent No. 936,445 I have shown a center selvage motion which is operated by the harness frames and there is in the motion set forth in that patent a single set of needles which move downwardly under the action of each harness frame and also move laterally in a direction which is determined by which of the harness frames is depressed. It is an important object of my present invention to eliminate the harness control for the selvage motion and substitute a single cam which will act to create both the vertically reciprocating movements and also the lateral displacing movements.

It is sometimes desirable to supply certain of the warp threads which are to form the center selvage from small spools mounted above the usual warp and having their ends threaded through the eyes which effect the interlacing of the center warp threads. As heretofore made these spools have been relatively stationary so that they do not move downwardly with the needles. The result of this arrangement has been to change the path through which the selvage warp threads traverse as they pass from the spools to the needles. In order to prevent this variation in the length of the yarns it is a further object of my invention to provide the spools with a mounting which will move with the needles so that the path along which the yarn travels is substantially the same for all vertical positions of the needle. In this way the correct tension may be retained in the warp threads supplied by the small spools.

With these and other objects in view which will appear as the description proceeds, my

invention resides in the combination and arrangement of parts hereinafter described and set forth in the claims.

In the accompanying drawings wherein a convenient embodiment of my invention is set forth,

Fig. 1 is a transverse section through the central portion of a loom provided with my invention,

Fig. 2 is an enlarged front elevation taken in the direction of arrow 2, Fig. 1,

Fig. 3 is an end elevation taken in the direction of arrow 3, Fig. 2, certain parts being shown in section for the sake of clearness,

Figs. 4 and 5 are detailed horizontal sections taken, respectively, on lines 4-4 and 5-5 of Fig. 3,

Fig. 6 is a detailed horizontal section taken on line 6-6 of Fig. 2,

Fig. 7 is a vertical section on line 7-7 of Fig. 1,

Fig. 8 is a detailed view on an enlarged scale looking in the direction of arrow 8, Fig. 1, and showing the relation of the sets of needles after they have crossed,

Fig. 9 is a view similar to a portion of Fig. 8 but with the sets of needles in the same position with respect to lateral displacement as shown in Fig. 8 but before said needles have been crossed to define the shed,

Fig. 10 is a view similar to Fig. 9 but with the sets of needles in a different position with respect to lateral displacement and with the sets crossing each other,

Fig. 11 is a detailed view looking in the direction of arrow 11, Fig. 1, showing the upper end of the driving rod which actuates the motion, and

Fig. 12 is a horizontal section on an enlarged scale taken on line 12-12 of Fig. 1.

Referring to Fig. 1, I have shown a loom-side 10 and a bottom shaft 11 which preferably rotates once every other pick of the loom. The arch 12 extends across the loom and may support at substantially the central portion of the loom a bracket 13 in which is secured for longitudinal horizontal adjustment a rod 14 held in said bracket by screw 15.

To the forward end of said rod 14 is se- 100

cured a bearing member 16 in which is held for vertical longitudinal adjustment a rod 17 positioned by screws 18 in said bearing 16. Said rod 17 is held in fixed position and extends downwardly as shown in Figs. 2 and 3.

There are two sets of needles, one extending downwardly from an upper support and the other set projecting upwardly from a driving rod and it is desirable to move said needles in opposite directions and to have one set above and the other set below the plane of the cloth at the time said sets are moved laterally. In order to produce these opposite reciprocating movements I extend through the rod 17 a pin 19 and mount for free rotation thereon a pinion 20. The rear side or right hand side as viewed in Fig. 3 of the pinion meshes with the driving rack 21 secured to a driving member 22 having upper and lower bearings 23 and 24, respectively, through which extends the rod 17. Said bearings are free to slide along the rod and the driving member receives vertical reciprocations by means of a driving rod 25 operatively connected to a stud 26 projecting from the bearing 23 and the lower end of which is attached as at 27 to a cam lever 28.

Lever 28 as viewed in Fig. 12 has the rear end thereof provided with a substantially cylindrical bore 29 through which extends a stud 30 having oppositely sloping conical portions 31 and 32, respectively. These conical portions permit the lever 28 to move laterally or in a direction parallel to the shaft 11 and they also act as a pivot around which said lever may move in a vertical plane.

The lever is provided with a shoe 33 having a vertical wall 34 and an upwardly facing horizontal surface 35. The shoe cooperates with a cam 36 which is formed substantially as shown in Fig. 7 with two dwell faces 37 and 38, respectively, which are laterally displaced with respect to each other. Said cam as shown in Fig. 7 has the lower face 37 in engagement with surface 34 while the upper face 38 is in a plane substantially parallel to the face 37 but displaced from the latter in a direction parallel to the shaft 11. The outer rim 39 of the cam has two points 40 and 41, respectively. The rim 39 is adapted for engagement with the surface 35 on the shoe and is the means by which the lever 28 is moved in a vertical plane.

The forward end of the lever 28 is acted upon by a diagonally disposed tension spring 42 having its upper end fixed and as shown in Fig. 7 so disposed as to tend to hold wall 34 against faces 37 and 38.

By means of the matter thus far described rotation of cam 36 will cause vertical movements of the lever 28, moving the latter downwardly whenever the points 40 or 41 engage the surface 35. It is also to be understood that the inclined surface 37a in the

periphery of the cam from the face 37 to the face 38 and vice versa occurs at the points 40 and 41 of the cam, the purpose being to give the lever 28 a lateral movement in a direction substantially parallel to the shaft 11 when said lever is depressed. When point 40 is depressing the lever and the cam is moving in the direction of arrow C, Fig. 7 and arrow D, Fig. 1, the control of the lever will be passing from face 37 to face 38, so that said lever will move positively to the right as viewed in Fig. 7. On the next pick of the loom when the lever 28 is depressed by point 41 the lever 28 will move to the left under action of spring 42.

As shown in Fig. 11 the upper end of the driving rod 25 is formed with a loop 43 which may extend rearwardly as at 44 in Fig. 1. A pair of upwardly projecting needles 45 are supported rigidly with respect to the rod 25 and are located so as to lie between the outer limits of the loop 43. The upper end of the link is pivotally connected to the stud 26 and may therefore swing in a vertical plane substantially parallel to the stud 30 as the lever 28 is displaced laterally by the inclined surface 37a of the cam 36. By the construction already described it will be apparent that the needles 45 and their eyes 46 will be moved not only up and down for each pick of the loom but will also be moved laterally in the loom with respect to the rod 17.

The other set of needles 47 which project downwardly are provided at their lower ends with eyes 48 and are secured to a driven member 49 having upper and lower slide bearings 50 and 51, respectively, through which extends the rod 17. Said member 49 is provided with a rack 52 which meshes with the pinion 20 and the relation of the parts is such that as the rack 21 moves downwardly with the lever 28 the pinion 20 will cause a corresponding upward movement on the part of the rack 52 and therefore of the needles 47. It will be seen that the force for moving the needles in opposite directions is derived from the same unit so that the motions are always simultaneous and in correct time with respect to each other.

As shown particularly in Fig. 5 the rod 17 has extending therethrough a pin 53 which engages rearwardly facing surfaces 54 on the member 49, the purpose of said pin being to prevent angular movement on the part of the member 49 around the rod 17 and thereby require the needles 47 to reciprocate through fixed paths as the loom operates. An adjustment by means of screws 18 will permit an angular change in the location of the pin 53 so as to vary the lateral relation between the needles 45 and 47. Likewise, the vertical relation of the sets of needles may also be adjusted by longitudinal movement of the rod 17 in its bearing 16. When the rod 17 which carries pinion 20 is raised, for in-

stance, the lower needles 45 will of course retain the same vertical position due to the fact that the surface 35 in contact with the rim 39 of cam 36 will limit upward movement thereof and as a result the pinion 20 as it rises will raise the needles 47. On the other hand, if it be desired to lower the needles 47, the rod 17 will be correspondingly lowered, the spring 42 being sufficiently strong to hold the lever in comparatively fixed position to require the pinion to move the rack 49 downwardly. It is to be understood that the parts are shown in an extreme position in Fig. 3 to correspond with the raised position of the lever 28 as shown in Fig. 1.

As previously stated it is sometimes desired to support some of the center selvage warp on small spools. In order to accomplish this result I provide the bearing 50 with a rearwardly extending horn 60 having a hub 61 from which project in substantially opposite directions two bearing rods 62. Each rod has mounted thereon a spool S which is held against a friction element 63 by a compression spring 64 and the latter may be stressed by a nut 65. The warp threads W drawn from the spools S extend downwardly through upper eyes E and lower eyes F, from whence they may be directed through the eyes 48 of the depending needles.

In order to prevent angular movement of the member 22 with respect to the rod 17 I provide said member with shoulders 66 which slide along surfaces 54 on the driven member 49.

It is to be understood that the warp threads which co-operate with the upper eyes 46 will usually be drawn from the main warp U of the loom or some source independent of the spools S, and it is further to be understood that the depending needles 47 may control threads which are formed as part of the main warp and are not necessarily fed with warp coming from the spool S. In fact under certain conditions the spools may be omitted.

In operation the lever 28 will receive its vertical and lateral movements as previously described, upward movement of the rod 25 carrying the needles 45 upwardly and acting through the racks and the pinion to move the needles 47 downwardly with the needles in the relation shown for instance in Fig. 8. During the next pick the needles will be separated to the position shown in Fig. 9, the lever 28 being controlled by a part of cam 36 intermediate the points. As the cam continues to rotate the lever 28 will move laterally by contact with inclined surface 37a so as to cause the lower finger 45 to move to the right of the position which they occupied in Fig. 9. After the lateral displacement the needles will again pass each other as suggested in Fig. 10. The effect of this is to move the warp threads U first on one side and then on the other side of the warps W controlled by the

needles 47. It will be seen from the construction of cam 36 that there is a lateral displacement of the sets of needles with respect to each other for each pick of the loom or for each flight of the shuttle so that the weaving effect is the customary cross weaving.

From the foregoing it will be seen that I have provided a selvage motion wherein there are employed two sets of needles, the sets moving in opposite directions. It will also be seen that a single cam and cam lever are sufficient to give the lower set of needles their lateral motion and to give to both sets of needles proper reciprocating movements. Furthermore, it will be seen that the pinion 20 and the racks with which it meshes cause simultaneously opposite equal movements of the needles and that because of the relation between the racks and the pinion a relative adjustment in a vertical direction between the eyes of the different sets may be accomplished merely by moving the rod 17. It will also be seen that the spools on which are wound the selvage warp threads move with the set of needles corresponding thereto so that there is no substantial change in the path traversed by the selvage warp threads from the spools as the needles move in a vertical direction.

Having thus described my invention it will be apparent that changes and modifications may be made therein by those skilled in the art without departing from the spirit and scope of the invention and I do not wish to be limited to the details herein disclosed, but what I claim is:

1. In a selvage motion for the warp threads of a loom, a pair of relatively movable warp controlling members, a lever, means to give said lever movements in one plane and also movements in another plane substantially perpendicular to the first plane, and connections between said lever and the members, said lever causing said members to have relative reciprocating and lateral movements.

2. In a selvage motion for the warp threads of a loom, a pair of relatively movable warp controlling members, a lever, a support for said lever, said lever being rotatable about the axis of said support in a plane substantially perpendicular to the axis and being movable in a direction transverse of the plane perpendicular to the axis of the support, connections between the lever and said members, and means to move said lever angularly about the axis of its support and also angularly in a direction parallel to the plane passing through the support.

3. In a selvage motion for the warp threads of a loom, a pair of relatively movable warp controlling members, a cam having points which are high and low relatively to the axis thereof and having two portions which are offset with respect to each other

in a direction parallel to the axis of the cam, and connections between said cam and the members to cause the latter to have relative reciprocating and lateral movements as the cam rotates.

5. A cam for a loom with selavage motion, said cam having points which are relatively high and low with respect to the axis of the cam, and said cam having two portions which are offset with respect to each other in a direction parallel to the axis of the cam, the offset portions being joined together at the relatively high point of the cam.
10. In a selavage motion for a loom, a pair of relatively movable warp controlling members, one member having a vertical movement and the other member having a vertical and also a transverse movement, a device between the members to cause the same to move in opposite directions, a cam, and a rigid connection between one of the members and the cam to give said other member its vertical and transverse movement and the first named member its vertical movement.
15. In a selavage motion for the warp threads of a loom, a pair of simultaneously oppositely movable controlling members for the warp threads, a rack for each member, a pinion meshing with the racks, one of the members and the racks being held against substantial transverse movement, and means to reciprocate the other member to cause opposite reciprocations of the racks and also cause said other member to move transversely.
20. In a selavage motion for the warp threads of a loom, a pair of simultaneously oppositely movable controlling members for the warp threads, a rack for each member, a pinion meshing with the racks, one of the members and the racks being held against substantial transverse movement, and means to reciprocate the other member to cause opposite reciprocations of the racks and also cause said other member to move transversely.
25. In a selavage motion for the warp threads of a loom, a pair of simultaneously oppositely movable warp thread controlling members, a rack operatively connected to each member, a pinion meshing with the racks, one of said members and the racks having vertical reciprocating movements, and means to give the other member vertical reciprocating movements and also transverse movements.
30. In a selavage motion for looms, a pair of oppositely reciprocable warp controlling members, geared connections operatively related to the members to cause them to have simultaneous opposite movements, a single actuator connected to one member to cause movement of said member and thereby effect opposite movements of said members through the geared connections, said actuator also effective to cause transverse movement of one of the members relatively to the other member.
35. In a selavage motion for the warp threads of a loom, a pair of relatively movable warp controlling members, a rotating cam having a rim and spaced dwell faces connected together by an inclined surface, and lifting portions on the rim, a single lever to engage the cam, said portions being effective through the lever to cause reciprocating

movements of the latter in a direction transverse to the plane of the warp threads and the surface being effective through the lever to cause relative lateral shifting of the members one with respect to the other in a direction substantially parallel to the plane of the warp threads.

10. In a selavage motion for the warp threads of a loom, a pair of relatively movable warp controlling members, a cam having two dwell faces spaced from each other and connected by an inclined surface, and a single lever between said cam and the members, said inclined surface of the cam effecting a relative lateral movement of the members through the lever.

15. In a selavage motion for the warp threads of a loom, a pair of relatively movable warp controlling members, a cam having a rim and two dwell faces connected to each other by an inclined surface, a single lever between said cam and the members, said surface of the cam effecting a relative lateral movement of the members, and said rim of the cam causing reciprocating movement of the members through the lever.

20. In a selavage motion for the warp threads of a loom, a pair of relatively movable warp controlling members, a lever, a support for said lever, said lever being rotatable about the axis of said support in a plane substantially perpendicular to the axis of the support and being movable in a direction transverse of said plane, connections between the lever and said members, and means to move said lever angularly about the axis of its support and also angularly in a direction parallel to the plane passing through the support, said means comprising a cam having a variable contour to cause movements of the lever about the axis of the support and having also a surface to cause movement of said lever in a direction transverse of the said plane.

25. In a selavage motion for the warp threads of a loom, a pair of relatively movable warp controlling members, connections between the members to cause the latter to move in opposite directions, a rotating element connected to one of the members, said element effective to cause simultaneous opposite movements of the members in a direction transverse of the plane of the warp threads, said element also effective to cause relative lateral movements of the members in a direction substantially parallel to the plane of the warp threads.

In testimony whereof I have hereunto affixed my signature.

ALBERT A. GORDON.
